UNITED STATES PATENT OFFICE.

AUGUST KAUCHER, OF NEW YORK, N. Y.

DESIGN FOR A SQUARE-PIANO CASE.

SPECIFICATION forming part of Design No. 14,118, dated July 24, 1883.

Application filed June 8, 1883. Term of patent 7 years.

To all whom it may concern:

Be it known that I, AUGUST KAUCHER, of the city, county, and State of New York, have invented a new and original Design for Square and Grand Piano Cases, of which the following is a full, clear, and exact description, reference being had to the accompanying drawings, making part of this specification, in which—

10 Figure 1 represents a perspective view of my improved design for a square-piano case, and Fig. 2 a detail side view of one of the rounded-off corners of the same.

15 Similar letters of reference indicate corresponding parts.

This invention has reference to an improved design for the case of square and grand pianos; and it consists of a piano-case having depressed panels in the rounded-off corners of the same.

20 A represents a square or grand piano case, the rounded-off corners of which are provided with a depressed panel, B, of any suitable configuration, preferably in keeping with the general style and character of the case. The depressed panels B may be covered with a veneer of different wood and color than that of the case, whereby the paneled corners become still more attractive.

I am aware that depressed panels in the straight sides of piano-cases of all kinds are well known, and these I do not claim; but I am not aware that such panels have ever been arranged in the rounded-off corners of square and grand piano cases, in which they are located vertically above the carved legs, so as to improve thereby the general appearance of these cases to a considerable extent.

Having thus described my invention, I claim as new and desire to secure by Letters Patent—

1. The design for a square piano, consisting of a case having rounded-off corners which are provided with depressed panels, substantially as shown and described.

2. The design for a square piano, consisting of a case having rounded-off corners which are provided with depressed panels vertically placed above the carved legs, substantially as shown and described.

In testimony that I claim the foregoing as my invention I have signed it this 4th day of June, 1883.

AUGUST KAUCHER.
